UNITED STATES PATENT OFFICE

164,764

SALT SHAKER OR THE LIKE

Valeria de Marsa, Los Angeles, Calif., assignor to Triangle Studios, El Monte, Calif., a copartnership

Application March 28, 1949, Serial No. 1,674

Term of patent 7 years

(Cl. D44—22)

To all whom it may concern:

Be it known that I, Valeria de Marsa, a citizen of the United States of America and a resident of Los Angeles, in the county of Los Angeles and State of California, have invented a new, original, and ornamental Design for a Salt Shaker or the like, of which the following is a specification, reference being had to the accompanying drawing, forming part thereof, in which:

Fig. 1 is a front elevational view of a salt shaker, or the like, showing my new design;

Fig. 2 is a top plan view; and

Fig. 3 is a side elevational view thereof.

I claim:

The ornamental design for a salt shaker or the like, substantially as shown.

VALERIA DE MARSA.
